CLAIM

The ornamental design for a table lamp as shown and described.

DESCRIPTION

FIG. 1 is a front perspective view of the table lamp, showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof; and,

FIG. 9 is a partial enlarged view of portion 9 in FIG. 2. The broken lines depict portions of the table lamp which form no part of the claimed design. The dot-dash broken lines depict the boundaries of the enlarged fragment shown in FIGS. 2 and 9 and form no part of the claimed design.

1 Claim, 9 Drawing Sheets
